UNITED STATES PATENT OFFICE

FREDERICK WRIGHT AND JOSEPH WALMSLEY, OF TORONTO, ONTARIO, CANADA.

FLOOR-SLEEPER ANCHORING AND SPACING DEVICE FOR CONCRETE.

979,628.

Specification of Letters Patent. Patented Dec. 27, 1910.

Application filed March 3, 1910. Serial No. 547,153.

To all whom it may concern:

Be it known that we, FREDERICK WRIGHT and JOSEPH WALMSLEY, both of the city of Toronto, in the county of York, in the Province of Ontario, Canada, have invented certain new and useful Improvements in Floor-Sleeper Anchoring and Spacing Devices for Concrete, of which the following is the specification.

10 Our invention relates to improvements in floor sleeper anchoring and spacing devices for concrete, and the object of the invention is to devise a simple, cheap and efficient means, whereby sleepers may be securely spaced and held in the concrete, so as to 15 form a solid and rigid groundwork for the wooden flooring which is superimposed thereupon.

Our invention consists of a metal strip 20 having a series of prongs struck up from the same preferably in pairs at equal distances apart, such strips being arranged parallel with one another with the prongs in lateral alinement to receive the sleepers over which 25 they are bent to hold the sleepers in place and the parts being otherwise constructed and arranged in detail as hereinafter more particularly explained.

Figure 1, is a perspective view of a portion 30 of a concrete bed upon which a flooring is to be laid, the upper layer of concrete being mostly removed to show the positioning of the strips. Fig. 2, is a somewhat similar view showing the sleepers held in place by the prongs being bent over them and secured to them. Fig. 3, is a longitudinal section. Fig. 4, is an enlarged perspective detail of portion of a strip.

In the drawings like letters of reference 40 indicate corresponding parts in each figure.

A is the bed of concrete, which is first laid and upon which strips B are placed. Each strip B has formed or struck up out of the same prongs B' arranged in pairs 45 close together, the one prong of the pair being struck up reversely to the other prong. Of course, we may not find it necessary to strike up two prongs, but only one prong but the two prongs will in our judgment 50 form a more secure means of fastening the sleeper. The sleeper we designate C.

The prongs are first bent up as shown in Fig. 4, so that the sleepers may be readily placed in position and then bent up more to 55 the vertical as shown in Fig. 1. After the

prongs have been bent up as shown in this latter figure another layer of cement is placed over the strips but allowing the prongs B' to protrude through such layer a sufficient distance, so that they may be 60 bent over the sleeper C in the fashion shown in Fig. 2. In this figure we have, of course, nails for securing the prongs to the layer and the bent ends of the prongs are preferably laid adjacent to each other instead of 65 over each other. It will, of course, be understood however that the manner of fastening the prongs to the sleeper or in other words securing the sleeper within the prongs may be varied without departing from the 70 spirit of our invention as may also the formation of the prongs or the like out of the metal strip.

When the sleepers are laid they are, of course, laid level and always form an air 75 space under the floor, which will prevent dry rot. According to the manner of laying the sleepers before our invention it was necessary to fill between them with cinders to maintain them in place and even then the so position of the sleepers was not secure and would frequently vary, so that it was a difficult matter to produce a true level on which to lay the floor.

By our invention all such difficulties are 85 avoided and the sleepers may be spaced and laid without skilled labor, which is an important desideratum. There is also no difficulty whatever of the sleepers loosening owing to shrinkage and the level will be 90 always maintained.

It will also be seen that as the strips pass through the concrete they also form a substantial reinforcement for the same.

What we claim as our invention is:

A floor sleeper anchoring and spacing device for concrete comprising a plurality of strips laid in a bed of concrete and having a series of prongs projecting through the concrete and located at desired distances apart, 100 and arranged in rows in lateral alinement, and sleepers extending crosswise of the strips on top of the bed of concrete, the said prongs being bent and secured to the sleepers as and for the purpose specified.

FREDERICK WRIGHT.
JOSEPH WALMSLEY.
